FREEZER ALARM AND MEANS FOR
ENERGIZING SAMEJackson Burgess, Glencoe, Ill., assignor, by mesne
assignments, to Burgess Battery Company,
Freeport, Ill., a corporation of Delaware

Application April 27, 1945, Serial No. 590,621

14 Claims. (Cl. 177—311)

1

This invention relates to alarms for freezers in which perishable goods such as food are preserved and stored in frozen condition for relatively long periods of time. It relates in particular to an alarm which is responsive to the improper operation of such a freezer. In the operation of freezers of this type, one of the most important factors is the detection of a rise in temperature before spoilage of the contents occurs. Such rise in temperature may be due to the failure of the power supply or of the refrigerating unit, the improper closing of a door or lid, or the inadvertent leaving open of a door or lid. Such freezers usually contain a relatively large amount of goods and if spoilage occurs, the loss may be serious. For that reason, it is desirable to have an alarm which is entirely reliable at all times.

In accordance with the present invention, an alarm is provided which is adapted to give a signal upon the occurrence of an undesired rise in temperature within the cabinet of a freezer of the class described. More broadly, an alarm is provided for the detection in any apparatus or location of a rise in temperature to a predetermined value which is below 32° F.

It is an object of the invention to provide an alarm for freezers which is entirely dependable and adapted to become operative upon an undesired rise in temperature regardless of how long the alarm has remained inactive before the rise occurs. This is desirable because freezers frequently operate for long periods of time without the occurrence of an undesirable rise in temperature.

It is another object of the invention to provide an alarm which is independent of the source of power for the operation of the freezer, and will operate without fail regardless of the cause of the undesirable rise in temperature.

It is a further object of the invention to provide an alarm which may be used with a gas fired refrigerator or freezer in locations where electrical energy is not available.

It is a further object of the invention to provide an alarm of the character described which is simple and inexpensive.

It is a further object of the invention to provide means for operating an alarm of the character described which comprises a deferred action primary battery which is adapted to become operative at any time upon the occurrence of a rise in temperature to a predetermined point, and does not suffer change or deterioration with the passage of time.

2

Further objects and advantages will become apparent as the following description progresses, which is to be taken in connection with the accompanying drawings, in which:

5 Fig. 1 is a view, partly sectional and partly diagrammatic, of an alarm apparatus in accordance with the invention;

Fig. 2 is an enlarged sectional view of the energizing means for the alarm shown in Fig. 1;

Fig. 3 is a diagrammatic view of a modified circuit arrangement for the alarm apparatus of the invention; and

Fig. 4 is a sectional view of a modified form of energizing means for the alarm apparatus of the invention.

In Fig. 1, a portion of the freezer cabinet 10 is shown having an opening 11 for the insertion and removal of the perishable goods which are to be preserved and stored, which opening is 20 adapted to be closed by a removable lid 12. Some freezers have separate compartments for freezing and storing the goods, and the alarm apparatus may be located in either of such compartments. The details of the freezer construction 25 are not a part of the invention and will not be described. A suitable support is provided, such as the shelf 13 attached to one of the cabinet walls as shown, such support preferably being located at an upper portion of the cabinet interior so as to interfere as little as possible with the storage of goods, and be fairly near to the opening 11, whereby the apparatus will be readily responsive to the improper closing of opening 11 or the inadvertent failure to close said opening.

35 Upon the shelf 13 is supported an energizing unit 15 which is adapted to energize the alarm upon the occurrence of an undesirable rise in temperature within the interior of the cabinet 10. The energizing unit 15 is connected by means 40 of conductors 16, 17, 18, and 19 to a suitable audible alarm, such as the electrically operated bell 20, and a suitable visible alarm, such as the electrically operated flag 21. The lower portion 22 of the shaft of the flag 21 is composed of electro- 45 magnetic material, such as soft iron, and the upper portion 23 is composed of nonmagnetic material, such as brass. The lower portion is encircled by the energizing winding 24, which is connected to connectors 17 and 16, the arrangement being such that, upon energization of the winding 24, a lifting force is applied to the shaft and the flag is raised. A projection 25 upon the shaft cooperates with one end of a latch member 26 which is pivotally mounted near its opposite 50 end upon a stationary member 27 and is sup-

ported in a substantially horizontal position by a lug 28 projecting forwardly (as seen in Fig. 1) from stationary member 27. When the flag 21 is raised, projection 25 lifts and passes latch 26, and the latch then drops back upon lug 28. When winding 24 is de-energized and flag 21 descends, projection 25 engages latch 26 and the flag is held in an elevated position until the latch is disengaged manually from projection 25. The said elevated position of the flag 21 may be understood by the attendant as being the alarm position, or means (not shown) may be provided for hiding the flag from view when in its lower position and exposing it to view when in the elevated position. A switch 29 is arranged in conductor 16 whereby the circuit may be opened if desired.

The alarm energizing unit 15 is shown in detail in Fig. 2. It comprises a rectangular open top container 30 closed by a cover 31 which may be joined by crimping its edges to the top edges of the container, whereby the interior of the container is effectively enclosed against the inward and outward movement of air. Container 30 and cover 31 are preferably composed of a highly heat conductive material, such as metal.

Within the container 30 is a second open top container 32 which fits within the exterior container 30 along the sides and bottom and is of lesser height than is the exterior container 30, as shown. The walls of container 32 are composed of an electrical insulating and electrolyte resisting material, such as phenol-formaldehyde resin, polystyrene resin, cellulose acetate, etc. The container 32 has a number of transverse partitions 33 extending upwardly from the bottom to a height somewhat less than that of the container walls, as shown. The partitions 33 may be integral parts of the container 32.

Within the compartments formed by the partitions 33 are arranged the cells of a deferred action electric battery. Each compartment contains a cell which is composed of cell elements which are in the form of flat plates which rest upon the bottom of the container 32 and are of a width substantially equal to the distance between the interior surfaces of the container walls and are of a height somewhat less than that of the partitions 33, as shown. The elements of each cell comprise, in succession, a cathode 34 which may be composed of carbon, a layer of depolarizing material 35 which may be a compressed mixture composed of finely divided manganese dioxide and carbon, a layer 36 of electrical insulating and electrolyte resisting bibulous material, such as porous blotting paper, and an anode 37 composed of magnesium. The elements of each cell are in firm pressure contact with each other. The anode 37 of one cell is connected to the cathode 34 of the next cell by a conductor 38, which may be welded or soldered to anode 37 and connected to the cathode 34 by first spraying molten metal such as copper, or electroplating a similar metal, upon the desired portion of the surface of the cathode and then soldering the conductor to the sprayed metal coating. The cells are thereby connected in series.

A terminal conductor 40 is connected to the cathode 34 of the first cell and a second terminal conductor 41 is connected to the anode 37 of the last cell. The conductors 40 and 41 pass through openings in the walls of inner and outer containers 30 and 32. Means are provided for sealing the openings in the container walls against

the passage of air and moisture. The means comprises a metal eyelet 43 which passes through the openings. The opening 44 in the metal container 30 is larger than the eyelet to provide an electrical clearance between the parts. Washers 45 and 46, which may be composed of phenol-formaldehyde resin, surround the end portions of the eyelets and are arranged between the flanges of the eyelet and the walls of containers 30 and 32. Preferably, a washer 47 of elastic material, such as the synthetic elastomer sold under the trademark "neoprene," is arranged between washer 46 and the surface of outer container 30. The construction is the same for each of the conductors 40 and 41 and said conductors pass through the interior of the eyelets 43. If the conductors do not fill the interior of the eyelets, the spaces may be filled with solder.

The conductors 40 and 41 are connected respectively to conductors 50 and 51 which pass through the wall of cabinet 10 and are electrically insulated therefrom by sleeves 52 and 53 and washers 54 and 55, composed of a suitable electrical insulating material. The conductors 50 and 51 are, in turn, connected to the conductors 16 and 17 which lead to the alarm signals.

Extending across the interior of outer container 30 and spaced above the inner container 32 is a partition or shelf 56 in the form of a screen or perforated sheet of a material which is resistant to the battery activating composition and preferably has a relatively high coefficient of heat conductivity, such as iron or steel. The shelf 56 may be soldered, welded or otherwise attached to the walls of container 30. Also extending across the interior of container 30 and suitably attached as by an adhesive, to the top edges of the inner container 32, is a sheet or membrane 57, which is composed of a material adapted to be ruptured by an accumulation of the liquid activating composition, such as paper, regenerated cellulose, polymerized vinyl acetate, or a thin foil of metal, such as magnesium. The attachment between sheet 57 and the edges of container 32 is preferably such as to provide a seal against the passage of moisture from the portion of container 30 above sheet 57 to the portion below.

Upon the shelf 56 rests an envelope 58 composed of frangible material, such as glass, which is substantially filled with the electrolyte or activating composition 59 for the battery. The activating composition 59 is an aqueous solution of an electrolyte compound, such as zinc sulfate, in a concentration such that the solution has a melting point between the normal operating temperature of the interior of the cabinet 10 and 32° F. For most of the freezers intended for domestic use in homes the normal operating temperature is around 0° F., while some of those used in commercial locker establishments operate at a somewhat lower temperature, in the neighborhood of -10° F. For closer control, it is preferable to employ a solution which has a relatively sharp melting point, so that upon a temperature rise to its melting point, melting to the liquid condition occurs relatively rapidly. Such solutions are the eutectic mixtures of the electrolyte compounds and water. Suitable mixtures of this character are aqueous solutions containing respectively 27.2% zinc sulfate (melting point 20.3° F.), 19.75% potassium chloride (melting point 12° F.), 18.6% ammonium chloride (melting point 3.6° F.), 22.5% barium chloride (melting point 17.3° F.), 19.0% magnesium sulfate (melting point 25° F.),

and 23.3% sodium chloride (melting point $-6.0^{\circ}\text{ F}.$).

While an eutectic mixture is a preferred form of electrolyte, other aqueous solutions may be used employing a suitable electrolyte compound in a concentration such that the melting point is between the normal operating temperature of the interior of the freezer cabinet and 32° F . Mixtures of electrolyte compounds may be employed to obtain the desired melting point, and the electrolyte compound may be supplemented by other substances which are well known as having the property of depressing the freezing point of water or aqueous solutions, such as alcohol, ethylene glycol, or the like.

In the use and operation of the alarm apparatus, the battery unit 15 is placed upon the shelf 13 and connected in the alarm circuit as described heretofore. The temperature of the battery unit becomes lowered to that of the interior of the cabinet 10, which may be assumed to be approximately 0° F . During this time the activating liquid 59 becomes frozen to a solid mass and undergoes a considerable expansion in volume. When water freezes, it undergoes an increase in volume equal to approximately 10% of its liquid volume, and the aqueous solutions here involved undergo an expansion which is substantially of the same order. Such expansion causes a rupture of the frangible envelope 58, but freezing begins at the surfaces of the activating composition 59, and a shell of frozen composition is first formed about a liquid interior, and although rupture of the envelope may occur before all of the composition has frozen, the liquid will be retained by the frozen shell and will not escape from the upper compartment of the container 30. After freezing, the activating composition will remain in said upper compartment in a frozen condition until the interior of the cabinet 10 undergoes an undesirable rise in temperature. This may be caused by failure of the refrigerating unit or of the source of power for the latter, or simply by an improper closing of the lid 12 or the inadvertent failure to close said lid. In any event, upon the occurrence of a rise in temperature to the melting point of the activating composition 59, the latter composition melts and the resulting liquid escapes from the ruptured envelope 58 and passes through the foraminous shelf 56 and accumulates upon supporting sheet 57. The sheet 57 is constructed so as to be ruptured by the weight of the activating composition after sufficient of such composition has accumulated upon it to render the battery satisfactorily operative. The time of rupture can be controlled conveniently by regulating the thickness of the sheet 57, or by providing a relatively thick sheet and providing score lines in it so that the sheet is weakened and rupture takes place at such lines after the proper amount of activating composition has accumulated upon the sheet.

Upon rupture of the sheet 57, the activating composition flows downwardly upon the several cells of the battery and is readily absorbed by the bibulous layers 36, and the said layers become the electrolyte spaces for the cells. The layers 35 of depolarizing material also become moistened by the activating composition and the battery thereupon becomes operative and energizes the alarm signals 20 and 21. The bell 20 rings until the circuit is broken, which may be accomplished by opening the switch 29 in conductor 16. In the same way, flag 21 is raised to its upper position

and remains there until the latch 26 is manipulated manually to permit the lowering of the flag. After the alarm has operated, the used battery unit 15 is replaced with a new one.

The alarm apparatus described above is simple and inexpensive and yet is thoroughly dependable, regardless of the length of time which may pass before it is called into operation. The battery unit described performs satisfactorily at the relatively low temperature at which the alarm operates. The battery unit is of the deferred action type and, since it is enclosed by the container 30, moisture does not collect in the electrolyte spaces and cause dissipation of energy. It, therefore, remains quite unaffected in its ability to deliver full energy when called upon to operate. In addition, operation of the alarm is independent of the source of power for the refrigerating unit and is not affected by the failure of such power source.

The alarm apparatus of the present invention is quite sensitive to a rise in temperature. The container 30 is composed of a material having a high coefficient of heat conductivity, preferably metal, whereby changes in the ambient temperature are conveyed promptly to the interior of the container. The foraminous supporting shelf 56 is also composed of a highly heat conductive material and said changes in ambient temperature are conveyed rapidly to the frangible envelope 58 and thence to the activating composition 59. As a result, any rise in temperature is conveyed quickly to the activating composition and the apparatus is highly sensitive to the temperature conditions which it is desired to detect.

A modification of the alarm apparatus is shown in Fig. 3. In this modification, the conductors 65 and 66 lead from the battery unit contained in the freezer cabinet, which may be similar to the unit 15 of Figs. 1 and 2, and are adapted to energize a relay 67. The alarms 68 and 69, which may be similar to the alarms 20 and 21 shown in Fig. 1, are connected in parallel with each other and in series with the relay 67 and a source of electrical energy, which may be the battery 10. Upon energization of the relay by the battery unit within the freezer cabinet, said relay closes the series circuit and energizes the alarm signals 68 and 69. In this modification, the battery unit within the freezer cabinet is not called upon to furnish the energy to operate the alarm signals, but only to energize the relay, and a battery unit of smaller capacity may be used. A switch 71 may be inserted in series connection between the battery 10 and the signals 68 and 69 and in parallel relation with the relay 67. The switch 71 may be closed from time to time to determine whether the battery 10 has retained sufficient energy to operate the signals.

In the modification of the invention illustrated in Fig. 4, a battery unit 89 is provided, which may be similar to the portion of battery unit 15 consisting of the inner container 32 and the cells contained therein. The unit 89 rests upon the bottom of container 90, which has a hinged lid 91 for closing the open top of the container as shown. A shelf 92 projects from the wall of container 90 and is spaced above the top of battery unit 89. The shelf 92 may be supported by a hinge 93 and bracket 104 as shown, to permit folding of the shelf upwardly. Supported pivotally upon shelf 92 at the point 94 is a cup-shaped cradle member 95. The pivot point 94 is arranged substantially at the end of shelf 92 and eccentrically with respect to the bottom of cradle

member 95 whereby somewhat more than half of said cradle extends beyond the end of shelf 92. The cradle member 95 has a partition 96 extending thereacross, said partition having an opening 97 in the bottom portion thereof. Partition 96 divides the cradle into a compartment 98 directly above shelf 92 and a second compartment 99 which projects beyond the end of shelf 92.

Within the compartment 98 is arranged a frangible envelope 100 containing a quantity of activating composition 101. Container 90, lid 91, shelf 92 and cradle member 95 are preferably composed of a highly heat conductive material. Conductors 102 and 103 are connected to the terminals of the battery unit 89 and extend through openings in the wall of container 90 and are adapted to be connected to an alarm circuit such as shown in Fig. 1 or Fig. 3.

In the use of the last modification, the battery unit 89 is first inserted in the container 90, the lid 91 being raised for this operation, and the shelf 92 also being raised upon the supporting hinge 93 if required for the passage of the battery unit 89. The parts 91 and 92 and the cradle 95 are then placed in the position shown in Fig. 4 and the frangible envelope 100, containing the activating composition in liquid form, is placed in compartment 98. In this position, the weight of the envelope 100 and activating composition 101 overbalances that of the portion of the cradle member 95 which projects beyond the end of shelf 92 and the cradle member remains in the position shown. The unit is then inserted into the freezer cabinet and connected to the alarm circuit. The activating composition becomes frozen as its temperature drops to that of the interior of the cabinet, and the frangible envelope 100 is fractured. Upon the occurrence of a rise in temperature to the melting point of the activating composition 101, the latter melts and flows into compartment 98 and through the opening 97 in partition 96 and into compartment 99. The arrangement is such that when substantially all of the activating composition has melted, or sufficient thereof to satisfactorily activate the battery unit 89, the weight of the portion of cradle member 95 which projects beyond the pivotal support 94 and its contents overbalances that of the remainder. Thereupon, the cradle member pivots clockwise (as viewed in Fig. 4) upon said support 94 and the activating composition is dumped into the battery unit 89 and serves to activate the latter and render it operative for producing the desired signal.

In the modification shown in Fig. 4, all of the parts of the signal energizing unit are contained in a closed container and moisture does not collect upon the interior thereof to cause frosting which might interfere with its proper operation. The pivoted cradle 95 will, therefore, function properly when called upon to do so.

Further modifications of the alarm apparatus may be made. For example, the battery need not be of the type specifically described. The anodes may be composed of zinc, aluminum, or other suitable metal, the cathodes may be composed of copper, silver, or other suitable substance, the depolarizing material may be silver chloride or other suitable material, and the activating composition may be different from those described heretofore. An example of a suitable battery is one of the Leclanche type having a zinc anode, a carbon cathode, a depolarizing element composed of a mixture of finely divided manganese

dioxide and carbon or graphite and an activating composition composed of an aqueous solution of ammonium chloride and zinc chloride having the proper melting point. The form and mechanical features of the battery may be different from those of the plate type of battery illustrated and described, and a deferred action battery of any suitable form and containing parts of any suitable composition may be employed.

10 In the battery unit 15, the supporting sheet 57 may be omitted if desired. If this is done, an activating composition having a relatively sharp melting point should be used, such as one of the eutectic mixtures described heretofore, whereby the activating composition is introduced into the battery at a rapid rate when the alarm temperature is reached. Also, while it is preferred to provide the moisture proof seals at the openings in the containers for the passage of conductors 40 and 41, they may be omitted if desired. Also, the battery may consist of a single cell or a plurality of cells connected in parallel, instead of in series as shown.

15 The alarm signal may be of a type different from that described. For example, the energizing unit may actuate a solenoid valve which is adapted, upon actuation, to cause the operation of a compressed air signal, such as a whistle. Other forms of signal may be employed.

20 25 30 35 40 Only a few examples of the alarm apparatus of the invention are described herein, and it is understood that these are for illustrative purposes and that the invention is not limited thereto, and that other modifications are included within its scope as the latter is set forth in the accompanying claims. The invention is not limited to alarms for freezers but is adapted generally for the detection of an undesired rise in temperature to a predetermined value below 32° F.

What is claimed is:

1. Means for energizing a work circuit upon rise of temperature to a predetermined value up to 32° F., comprising a substantially closed container, a deferred action battery in said container, a frangible envelope in said container, an aqueous activating composition in said frangible envelope and adapted to rupture said envelope upon freezing, said activating composition having a melting point of approximately said predetermined temperature, means in said container for retaining said activating composition following melting thereof after rupture of said frangible envelope, said retaining means being adapted to release said composition for passage to said battery upon accumulation of a quantity thereof by said retaining means.

2. Means for energizing a work circuit upon rise of temperature to a predetermined value, comprising a deferred action battery, an aqueous activating composition for said battery having a melting point of approximately said predetermined temperature, means for retaining said activating composition outside of said battery, said means being adapted to be ruptured upon freezing of said activating composition.

3. Means for energizing a work circuit upon rise of temperature to a predetermined value, comprising a deferred action battery having positive and negative electrodes, an aqueous activating composition for said battery having a melting point of approximately said predetermined temperature, means for retaining said activating composition out of contact with said electrodes, said retaining means being adapted to be af-

fected by the freezing of said activating composition to permit the passage of said activating composition into contact with said electrodes upon subsequent melting of said activating composition.

4. Means for energizing an alarm signal for a deep freezer alarm, comprising a deferred action battery, an aqueous activating composition for said battery having a melting point of approximately between -10° F. and 32° F., means for retaining said activating composition outside of said battery, said means being adapted to be ruptured upon freezing of said activating composition, and means for conducting said activating composition into said battery upon melting of said activating composition.

5. An energizing unit for an alarm signal for a freezer, comprising a deferred action battery, an aqueous activating composition for said battery having a melting point between approximately 32° F. and the normal operating temperature of the freezer, means for retaining said activating composition outside of said battery, said means being adapted to be ruptured upon freezing of said activating composition.

6. The energizing unit as claimed in claim 5, in which means are provided for delaying delivery of the melted activating composition to the battery until a substantial amount thereof has accumulated.

7. The energizing unit as claimed in claim 5, in which a separating member is arranged between the retaining means and the battery, said separating member being adapted to be ruptured by the accumulation of melted activating composition in contact therewith.

8. The energizing unit as claimed in claim 5, in which the retaining means for the activating composition is contained in a receptacle the walls of which are composed of a highly heat conductive material, such as metal.

9. The energizing unit as claimed in claim 5, in which an enclosure is provided for the energizing unit which is substantially sealed against the entrance of moisture.

10. A freezer alarm comprising, in combination, a freezer cabinet, an alarm signal outside of said cabinet, an electric supply circuit for said signal, a deferred action battery within said cabinet and operatively associated with said supply circuit, a frangible envelope in said cabinet, an aqueous activating composition for said battery in said envelope and adapted to fracture said envelope upon the expansion of said activating composition occurring with freezing thereof, said composition having a melting point between 32° F. and the normal operating temperature of the interior of said cabinet.

11. A freezer alarm, comprising, in combination, a freezer cabinet, an alarm signal outside of said cabinet, a deferred action battery within said cabinet and electrically connected to said signal, an aqueous activating composition for said battery located within said cabinet and outside of said battery, said activating composition be-

ing in frozen condition and having a melting point between 32° F. and the normal operating temperature of the interior of said cabinet, a retaining member for said activating composition, said retaining member being adapted to be ruptured by the accumulation of melted activating composition thereagainst and thereby release said activating composition for passage to said battery.

10 12. A freezer alarm, comprising, in combination, a freezer cabinet, an alarm signal outside of said cabinet, a deferred action battery within said cabinet and electrically connected to said signal, an aqueous activating composition for said battery located within said cabinet and outside of said battery, said activating composition being in frozen condition and having a melting point between 32° F. and the normal operating temperature of the interior of said cabinet, retaining means for said activating composition adapted to be actuated by the weight of a predetermined quantity of melted activating composition for releasing said activating composition for passage to said battery.

15 13. A freezer alarm, comprising, in combination, a freezer cabinet, an alarm signal outside of said cabinet, a deferred action battery within said cabinet and electrically connected to said signal, an aqueous activating composition for said battery located within said cabinet and outside of said battery, said activating composition being in frozen condition and having a melting point between 32° F. and the normal operating temperature of the interior of said cabinet, a retaining member for said activating composition, said retaining member being adapted to release said activating composition upon accumulation of melted activating composition thereagainst.

20 14. A freezer alarm, comprising, in combination, a freezer cabinet, an alarm signal outside of said cabinet, a deferred action battery within said cabinet and electrically connected to said signal, an aqueous activating composition for said battery located within said cabinet and outside of said battery, said activating composition being in frozen condition and having a melting point between 32° F. and the normal operating temperature of the interior of said cabinet, and means for delaying delivery of the melted activating composition to said battery until a sufficient quantity thereof has accumulated to render said battery operative.
